UNITED STATES PATENT OFFICE.

ALFRED PETER, OF THREE RIVERS, MICHIGAN, ASSIGNOR, BY MESNE ASSIGNMENTS, TO FAIRBANKS, MORSE & CO., OF CHICAGO, ILLINOIS, A CORPORATION OF ILLINOIS.

OIL-ENGINE.

1,324,978.

Specification of Letters Patent. Patented Dec. 16, 1919.

Application filed May 6, 1918. Serial No. 232,724.

To all whom it may concern:

Be it known that I, ALFRED PETER, a citizen of the Republic of Switzerland, residing at Three Rivers, in the county of St. Joseph 5 and State of Michigan, have invented a certain new and useful Improvement in Oil-Engines, of which the following is a specification.

This invention relates to explosive engines 10 in which oil is used as a fuel, and particularly to that class of engines in which, on starting, the oil charges are fired by being thrown into contact with a temporarily heated igniting device, but are, after the 15 engine is started, fired by the heat of the compressed gases or by contact with surfaces exposed to the heat of combustion of regular operation of the engine.

The objects of the invention are to provide 20 a mechanism which does not involve moving parts, by which the engine may be initially fired by an externally heated member, while the permanent firing of the engine is done by the heat of the compressed 25 gases or by contact with surfaces exposed to the heat combustion of regular operation of the engine; to provide a novel means for protecting the cylinder heads from the heat produced by the combustion of the engine so 30 that if a fracture occurs due to excessive heat, it will take place in a removable part and a part which will not permit the escape of gas from the engine, thus requiring the stoppage until repairs can be made. A further 35 object of the invention is to provide a novel method of water-jacketing the combustion chamber. The invention further consists in the features and details of construction hereafter more fully set forth in 40 the specification and claims.

Referring to the drawings, in which similar numerals refer to the same parts, the single figure is a central sectional detail view through the combustion end of an engine 45 cylinder 10, equipped with mechanism illustrating this invention in its preferred form. The cylinder 10, just referred to, is closed by a cylinder head 12, the cylinder and head being suitably water-jacketed as 50 shown at 13, 14, 15. Reciprocatably mounted inside of cylinder 10 is a piston 16, having a central projecting flattened end portion 18 closing a conical opening 20 formed in the cylinder head. Superimposed upon the cylinder 55 head is a casting 22 having within it

a generally spherical combustion chamber 24 of a suitable size for use in firing the engine. In the preferred form of the invention shown, this casting 22 is so made that a portion of it, the lower half as shown in the drawing, is in the form of a conical member 26 which enters conical recess 20 in the cylinder head, there being through this conical opening 20 a central passageway 28 leading into the cylinder 10. It is to be noted that the walls of this conical member 26 protect the walls of the conical opening 20 of the cylinder head from heat arising in the combustion chamber 24, with the result that if anything cracks under the action of excessive heat in the combustion chamber 24, it is the wall portions 26 in casting 22 which can be easily removed for repair or replacement, rather than the heavier and more expensive cylinder head 12. Furthermore, if cracks do appear in the conical member 26, gases within the combustion chamber 24 are still prevented from escaping by the walls of conical opening 20 of the cylinder head, whereas were conical members 26 not provided, gases in chamber 24 would, if the crack occurred in the conical walls of the opening 20 of the cylinder head 12 escape into the water jacket 13 and cause trouble. The casting 22 is detachably secured to the cylinder head by any suitable means not shown in detail in the drawing.

The conical recess 20 and the conical interfitting part 26 further serve a useful function in that if the heat breaks the member 26, the parts thereof are retained against the conical walls of the opening 20 and do not readily fall into the cylinder, and, thus, there do damage, as would be apt to be the case were a straight sided or oppositely flaring wall connection provided.

At the top of combustion chamber 24 and in alinement with passageway 28, heretofore described, is an injector nozzle 30 adapted, when supplied with fuel oil or the like, to throw it through combustion chamber 24 and toward passageway 28 and piston 18, this fuel being ignited on introduction by hot compressed gases or by contact with the piston on the other hot surfaces causing a pressure rise in the chamber 24—28, which, in the ordinary manner, forces piston 18 downward as viewed in the figure within cylinder 10.

As the operation just described cannot 110

take place until the surfaces have become heated by previous combustion, it is necessary to provide initial starting means, and this consists in the use of a hot plug or spot 5 device 34 located in the upper portion of the combustion chamber and an injector nozzle 36 suitably located opposite it adapted to discharge oil or other fuel material across the chamber 24 and into contact with the 10 heating device 34 or parts of the casting 22 immediately adjacent thereto. Outside of the mechanism heretofore described, a suitable supply pipe 36 is provided having one branch controlled by a suitable valve, as 15 38, adapted to deliver fuel to the nozzle 36 and another branch, as 40, preferably controlled by a suitable valve 42, delivering fuel to nozzle 30. The device will work, in practice, when both valves 38 and 42 are omitted 20 or are both open, but it is preferable to provide them and operate the device with valve 42 closed and 38 open during the starting operation; reversing them after the engine has become warm enough to ignite regularly 25 from the heat of previous combustions. Under this last condition, heat or heat-producing agents supplied to device 34 may, of course, be cut off as it is unnecessary until, after the engine has cooled off, it is desired 30 to again start it.

The upper portion of casting 22 is provided with water jacketing ports and passageways 40, 42, 44, 46 terminating in a discharge pipe 48, so that cooling liquid may 35 be passed from the water-jacketing spaces 13, 14, 15 of the cylinder head around the upper end of the combustion chamber 24, thus cooling it without interfering with the starter-heating device 34. In practice, it has 40 been found that this structure materially increases the efficiency of the device.

Having thus described my invention, what I claim as new and desire to secure by Letters Patent, is:—

45 1. In a device of the class described, an engine cylinder closed at one end, except for a relatively small opening, a piston in said engine cylinder adapted to travel into proximity with said opening, a combustion chamber outside the cylinder end communicating with said opening, means for injecting fuel material through said combustion chamber and said opening toward said piston, means for temporarily heating a part exposed to 50 the combustion chamber, another means for injecting fuel material through the combustion chamber into contact with said temporarily heated part, means for supplying fuel material through both of said injecting means, and means for selectively controlling the supply of fuel to said injecting means.

55 2. In a device of the class described, an engine cylinder closed at one end except for a relatively small opening, a piston in said 60 engine cylinder adapted to travel into prox-

imity with said opening, a combustion chamber outside the cylinder end communicating with said opening, means located in substantially the axis of the cylinder for injecting fuel material through said combustion 70 chamber and said opening toward said piston, means for temporarily heating a part exposed to the combustion chamber, and another for injecting fuel material through the combustion chamber into contact with said 75 temporary heating means located approximately at right angles to the first injecting means.

3. In a device of the class described, an engine cylinder closed at one end except for 80 a relatively small opening, a piston in said engine cylinder adapted to travel into proximity with said opening, a combustion chamber outside the cylinder end communicating with said opening, means located in 85 substantially the axis of the cylinder for injecting fuel material through said combustion chamber and said opening toward said piston, means for temporarily heating a part exposed to the combustion, another 90 means for injecting fuel through the combustion chamber into contact with said temporary heating means located approximately at right angles to the first injecting means, means for supplying fuel material 95 through both of said injecting means, and means for selectively controlling the supply of fuel to said injecting means.

4. In a device of the class described, an engine cylinder closed at one end, except 100 for a relatively small opening, a piston in said engine cylinder adapted to travel into proximity with said opening, a combustion chamber outside the cylinder end communicating with said opening, means for injecting fuel material through said combustion chamber and said opening toward said piston, means for temporarily heating a part 105 in communication with the combustion chamber, another means for injecting fuel through the combustion chamber into contact with said temporarily heated part, and a water-jacket device for the head of the engine cylinder and that portion of the combustion chamber which is outside the engine 110 cylinder head exclusive of the portion immediately in proximity to said temporary heating means.

5. In a device of the class described, the combination of an engine cylinder head having a perforation therein, and a combustion chamber member having a opening therein adapted to register with the opening in the cylinder head, said opening in the combustion chamber member being through a projecting portion thereof forming substantially half of the combustion chamber which enters and serves as a lining for the opening in the cylinder head mechanism, for the purposes set forth. 120 125 130

6. In a device of the class described, the combination with an engine cylinder head having a perforation therein and a combustion chamber member having an opening 5 therein adapted to register with the opening in the cylinder head, said opening in the combustion chamber member being through a conical projecting portion thereof which enters and serves as a lining for a corresponding conical opening in the cylinder head mechanism, adapted to retain any parts 10 broken from the combustion chamber, to prevent their entrance to the engine cylinder, for the purposes set forth.
- 15 7. In a device of the class described, the combination of an engine cylinder head having a perforation therein, a combustion chamber member having an opening therein adapted to register with the opening in the 20 cylinder, said opening in the combustion chamber member being through a projecting portion thereof forming substantially half of the combustion chamber which enters and serves as a lining for the opening in the 25 cylinder mechanism, and means for firing fuel material within the combustion chamber preparatory to its passage into the cylinder, for the purposes set forth.

ber preparatory to its passage into the cylinder, for the purposes set forth.

8. In a device of the class described, the combination with an engine cylinder head 30 having a perforation therein and a combustion chamber member having an opening therein adapted to register with the opening in the cylinder head, said opening in the combustion chamber member being 35 through a conical projecting portion thereof which enters and serves as a lining for a corresponding conical opening in the cylinder head mechanism, adapted to retain any parts broken from the combustion chamber 40 to prevent their entrance to the engine cylinder, and means for firing fuel material within the combustion chamber preparatory to its passage into the cylinder, for the purposes set forth.

In witness whereof I have hereunto subscribed my name in the presence of two witnesses.

ALFRED PETER.
